Primary Examiner—Alan P. Douglas*Assistant Examiner*—Lavone D. Tabor*Attorney, Agent, or Firm*—Foley & Lardner[57] **CLAIM**

The ornamental design for a handle for an oval brush, as shown and described.

DESCRIPTION

FIG. 1 is a top perspective view of a first embodiment of a handle for an oval brush showing our new design;
 FIG. 2 is a front elevational view thereof, the rear elevational view being a mirror image of the front view shown;
 FIG. 3 is a top plan view thereof;
 FIG. 4 is a bottom plan view thereof;
 FIG. 5 is a left end elevational view thereof;
 FIG. 6 is a right end elevational view thereof; and,
 FIG. 7 is a front elevational view of a second embodiment of the handle for an oval brush, the rear elevational view being a mirror image of the front view;
 FIG. 8 is a top plan view of FIG. 7;
 FIG. 9 is a bottom plan view of FIG. 7;
 FIG. 10 is a left end elevational view of FIG. 7; and,
 FIG. 11 is a right end elevational view of FIG. 7.
